UNITED STATES PATENT OFFICE

94,192

DESIGN FOR A BATHROOM FIXTURE

Carmen Di Antonio, Trenton, N. J.

Application April 9, 1934, Serial No. 51,355

Term of patent 3½ years

To all whom it may concern:

Be it known that I, Carmen Di Antonio, a citizen of the United States, residing at Trenton, in the county of Mercer and State of New Jersey, have invented a new, original, and ornamental Design for a Bathroom Fixture, of which the following is a specification, reference being had to the accompanying drawing, forming part thereof.

I claim:—

The ornamental design for a bath room fixture as shown.

CARMEN DI ANTONIO.
